DECORTICATING MACHINE

Anton Burkhardt, New York, N. Y.

Application August 1, 1939, Serial No. 287,799

10 Claims. (Cl. 19—24)

My present invention relates to machines for treating vegetable stalks containing fibre, and more particularly to an improved machine for decorticating vegetable stalks such as hemp, flax, ramie, and the like.

My present invention is designed to decorticate vegetable stalks in the dry or semi-dry state, as distinguished from the wet or wetting processes, and separate the fibres from the shives by mechanical process, as distinguished from the heretofore used chemical process.

An important feature of my invention is an improved floating anvil over which the stalks are fed to the scutching rotors.

A further feature of my invention is an improved anvil provided with means for delivering air under pressure to the face thereof.

A further feature of my invention is an improved assembly of scutching rotors which co-operate with each other to provide a continuous or sinuous path for the fibre and for operating to remove the shives from the fibre while such fibre is lying in the sinuous path.

A still further feature of my invention is an improved scutching rotor provided with means for ejecting air therefrom in a direction generally radially of the axis of rotation thereof.

A further feature of my invention is an improved scutching rotor having a plurality of blades extending radially outward therefrom and with means for emitting air from a plurality of orifices arranged along the leading edge thereof.

A still further feature of my invention is an improved means for collecting the shives removed from the fibrous material and removing the same from the machine.

Another feature of my invention is the air-blast cleaning of the adhering shives from the fibre, while the fibre itself is held taut between the rotor blades.

Another feature of this invention is improved means for preventing the winding of decorticated fibre on the rotors when such rotors revolve at high speed, thereby increasing the output of the machine.

Other features of the invention will appear as the description of the invention progresses.

In the accompanying drawings:

Fig. 1 represents in sectional side elevation of an improved decorticating machine embodying my present invention;

Fig. 2 is a sectional elevation of a portion of Fig. 1 on an enlarged scale and illustrating a

means for delivering air under pressure to a resiliently faced anvil;

Fig. 3 is an enlarged view of a fragment of a machine similar to that illustrated in Figure 1 and showing a set of scutching rotors, one of which is in direct operative association with an anvil the face of which is provided with a plurality of rows of orifices for delivering air under pressure to the material being worked upon and said set of rotors being provided with radially extending sets of orifices through which air is emitted under pressure;

Fig. 4 is a perspective view of one of the rotors shown in Fig. 3;

Fig. 5 is a sectional side elevation on an enlarged scale of a portion of a machine similar to that illustrated in Fig. 1 and showing a pair of scutching rotors in operative relation with respect to each other and to an anvil and with each of the rotors provided with sets of orifices for delivering air under pressure radially of the axis of rotation and substantially tangentially; and

Fig. 6 is a sectional end elevation taken on the line 6—6 and looking in the direction of the arrows on such section line.

Referring to the drawings, 10 designates generally a framework in which the operating elements of my improved invention are mounted, such framework for clearness of illustration and convenience of description being shown as a framework of sheet material. The framework is shown practically in the form of a casing.

At an upper end of the framework 10 is provided an opening 11, the peripheral edges of which are provided with resilient flaps 12. Within the framework 10 and adjacent the opening 11 are arranged in vertical alignment shafts 13 and 14, the shaft 13 being vertically adjustable by means of the adjusting screw 15 and spring 16. Mounted on the shaft 13 is a crushing roll 17 while secured to the shaft 14 is a crushing roll 18. The crushing rolls 17 and 18 are normally in engagement with each other and form a throat into which stalks of fibrous material 19 are fed by the conveyor 20, over the feeding platform 20a. The crushing rolls 17 and 18 have their periphery engaged by the resilient flaps 12.

Still within the framework 10 and interiorly of the crushing rolls 17 and 18 are rollers 21 and 22 one or both of which may be rubber surfaced, the rollers being relatively adjustable toward and from each other by means of the adjusting screw 23. The rollers 21 and 22 receive the

fibres 19 from the crushing rolls 17 and 18 and serve to prevent individual stalks of the layer of stalks from being drawn into engagement with the anvil by the rapidly rotating decorticating rotors. In other words, the rollers 21 and 22 ensure that the layers of stalks 19 shall be fed as a unit to the decorticating rotors.

Adjacent of the delivery end of the rollers 21 and 22 is arranged an anvil 24. Referring to Figure 2, it will be noted that such anvil 24 comprises a block, the upper surface of which is inclined upwardly from the rollers 21 and 22, as indicated by the reference numeral 25, and is provided on its front face with a resilient facing 26. Also, said block is provided with a plurality of sets of orifices, such sets being numbered 27 and 28 respectively. These sets each consist of a number of orifices extending across the face of the block and the orifices are connected to a manifold 29 which in turn is connected by pipe 30 to a suitable source, preferably of compressed air. The upper set of orifices 27 communicates with aligned orifices in the resilient anvil face 26. The set of orifices 28 is provided with tubular members 31 which terminate just below the lower edge of the resilient anvil face 26.

Mounted in suitable bearings in the framework 10, such bearings for the simplicity of illustration and description not being shown, are shafts 32, 33, and 34. These shafts are arranged parallel to each other and on these shafts, respectively, are mounted the scutching rotors 35, 36, and 37.

35 The shafts 32, 33, and 34 are interconnected by suitable gearing or equivalent means so as to rotate at the same peripheral speed and in the direction of the arrows shown, for example in Figure 1. Further, the shaft 32 is provided 40 with suitable means for driving the rollers 21 and 22 and crushing rollers 17, 18 all at the proper speed and in the proper direction. The shaft 32 is driven through the transmission mechanism 38 from the prime mover 39, which 45 in turn has power delivered thereto from any suitable source.

The scutching rotor 35 has the scutching bars thereof associated with the resilient anvil face 26, and the anvil face 26 is always in engagement with the respective scutching bars of the scutching rotor 35 throughout the effective scutching movement thereof. The peripheral speed of the scutching rotor 35 is measurably greater than the linear speed of travel of the stalks 19 of fibrous material. Therefore, as the stalks 19 are fed over the top edge of the resilient anvil face, not only will the shive portions be "snapped" therefrom but there will be a combing action on the stalks by the scutching bars of the scutching rotor as long as the scutching rotor is in engagement with the resilient face 26 of the anvil.

As shown in Fig. 1, the scutching rotors 35, 36 and 37 have the scutching bars thereof interengaging, thus forming a sinuous path through which the now partially scutched fibrous material 19 is led. The rate of feed of the stalks 19 being constant and the peripheral speed of the scutching rotors 35, 36 and 37 also being constant but greater than the speed of travel of the stalks 19, it is apparent that there will be a combing, and therefore a scutching, action on the stalks 19 by the scutching bars of the scutching rotors as long as the fibrous material lies in

the sinuous path, the stalks being held taut by the stated instrumentalities.

After leaving the set of rotors 35, 36 and 37, the now completely decorticated fibrous material 19a is fed downwardly, as shown in Fig. 1, between the endless conveyor belts 40 and 41, being delivered from without the framework 10 through an opening 42 in an auxiliary casing 43 attached to the framework 10. The endless conveyors 40 and 41 are driven at the same speed 10 and in the same direction, as indicated by the arrows, from the prime mover 39 through the intermediary of the sprocket chain 44.

Arranged on either end of the framework 10 and within the framework are the casings 45 and 46 respectively.

In the casing 45 adjacent the top thereof is an opening 47 and also an opening 48, the opening 48 lying beneath the opening 47. The openings 47 and 48 extend the full width of the framework 10. Associated with the openings 47 and 48 are endless conveyor belts 49 and 50 respectively. Suitable means is provided for moving the upper reach of each of the conveyor belts 49 and 50 in the direction of the arrows 25 shown in Figure 1 so as to deliver the material deposited thereon through the openings 47 and 48 respectively into the casing 45. The conveyor 49 lies directly beneath the scutching rotor 35 while the conveyor 50 lies beneath but spaced 30 apart from the conveyor 49.

In the casing 46 are provided openings 51, 52 and 53. The opening 52 is below the opening 51 and the opening 53 is below the opening 52. Associated with the openings 51, 52 and 53 are 35 the endless conveyor belts 54, 55 and 56 respectively. The conveyor 54 is positioned above the scutching rotor 37 while the conveyor 55 is positioned below such scutching rotor 37. The conveyor 56 is positioned below the conveyor 55 and 40 is spaced apart therefrom as shown. Suitable means is provided for operating the conveyors 54, 55 and 56 and for moving the upper reach thereof in the direction of the arrows shown in Figure 1 so as to deliver the material deposited 45 thereon through the openings 51, 52 and 53 respectively and into the casing 46.

As the shives, designated by the numeral 55, are removed from the fibrous material 19, the rapid rotary movement of the scutching rotors 35 and 37 cause some of the shives to be blown upwardly as shown in Fig. 1 to be deposited on the conveyor 54. Also, some of the shives will be directed by the scutching rotors 36 and 37 onto the conveyors 49 and 55 respectively. Those of the shives which are not deposited in either of the troughs above noted will fall downwardly between the conveyors 49 and 55 and I have provided the following instrumentalities to collect such shives and deposit the same onto the conveyors 50 and 56.

Such means comprises the parallelly arranged shafts 56 and 57 respectively each having secured thereto and rotatable therewith a hub portion 58 to which is attached the radially extending blades 59. The shafts 56 and 57 are rotated from the transmission means 38 through the sprocket chain 60. From an inspection of Fig. 1, it will be apparent that as the blades 59 70 rotate, the shives that pass beyond the conveyors 49 and 55 will be deposited on the blades 59 and, as the shafts 56 and 57 rotate, such shives will be deposited on the conveyors 50 and 56. The material deposited in the casings 45 75

and 46 may be removed therefrom in any suitable manner.

As will be noted from an inspection of Figure 1, the blades 59 on the shafts 56 and 57 respectively slightly intermesh with each other, and, therefore, engage with the fibrous material 19a. The peripheral speed of the blades 59 is greater than the linear speed of the fibrous material 19, and, therefore, there will be a pronounced scraping or 0 combing action of the fibrous material 19 by the ends of the blades 59 so that any shives that may be loosely attached to the fibrous material 19a will be scraped off therefrom and deposited on the blades 59.

5 In place of the anvil shown in Figures 1 and 2, I may utilize the form of anvil shown in Figure 3, where the anvil block is designated by the reference numeral 61 and is provided with an arcuate operating face designated 62, and also with a co- 0 operating stalk-retaining roll 61a. Such anvil block is provided with a manifold 63 connected through a pipe 64 to a suitable source of air under pressure. The face of the anvil is provided with a plurality of horizontal rows of orifices 65 5 at various levels communicating with the manifold 63 and through which air under pressure is delivered from the face of the anvil. Such air effects an air combing of the fibre freeing it from shives.

10 In place of the scutching rotors shown in Figures 1 and 2, I may utilize the scutching rotors shown in Figure 4, wherein is shown a scutching rotor in perspective and designated by the reference numeral 66. Such scutching rotors 66 are 5 provided with four scutching bars as shown in Figure 4 and also in Figure 3, but obviously may have as many bars as desired, similar to the scutching rotors shown in Figures 1 and 2. The hub portion of the type of scutching rotor indicated by 66 is preferably hollow and is provided with a plurality of rows of orifices 67 communicating with the hollow interior of the rotors and located each set between adjacent bars thereof. It is obvious, therefore, that as the scutching rotors rotate, air under pressure will be ejected 10 through the orifices 67 in radial directions and will assist in blowing off from the fibrous material 19 any shives 95 that may have been loosened by action of the scutching rotors.

15 In Figure 3, I have shown three such rotors 66 arranged in a position relative to each other, similar to the rotors 35, 36, and 37 shown in Figures 1 and 2.

As a modification of the type of rotor illustrated in Figure 4, and shown in operative relation with similar rotors in Figure 3, I may utilize a scutching rotor designated by the numeral 68 in Figures 5 and 6. In the scutching rotor 68 there is provided the radially extending sets of orifices 69 which are designed to deliver air practically at the leading edge of the bars of the rotors.

20 In Figure 6, I have shown the scutching rotor 68 having associated therewith a tubular member 73 connected through elbow 74 to a pipe 75 leading from a suitable source of pressure, as air, delivered from a compressor 71.

The compressor 71 shown in Figure 6 may be identical with and the same as the compressor 71 shown in Figure 1 and which compressor is utilized as a means for delivering air or other suitable fluid under pressure to the intake pipe 30 for the anvils.

25 In Figure 5, I have shown but two scutching rotors 68 in operative relation to each other, and

find under some conditions of service that two rotors arranged and constructed as above described and as illustrated in Fig. 5 are sufficient to effectively decorticate fibrous material.

The use of air or other suitable fluid under pressure in connection with the anvil and in connection with the decortinating rotors has the effect of cleaning and loosening the shives from the fibres and enables a better decortinating action to be effected, and also prevents particularly the air under pressure emanating from the rotors any possible danger of winding of the fibrous material onto the rapidly rotating rotors. It has been found that the air or other suitable fluid under pressure has the effect of expanding or exploding the stalks of the fibrous material enabling the decortinating rotors to effect a quicker and cleaner decortinating action and places the fibrous material in such a condition as to allow the shive material thereon to be more readily and easily attacked by the decortinating rotors.

30 Whereas I have described my invention by reference to specific forms thereof, it will be understood that many changes and modifications may be made without departing from the spirit of the invention.

I claim:

1. An apparatus for treating fibrous material comprising in combination an anvil, a plurality of scutching rotors provided with scutching bars and comprising a group having the scutching bars interlocking with each other to provide thereby a sinuous path through which fibrous material is led during the scutching operation.

35 2. An apparatus for treating fibrous material comprising in combination an anvil provided with a resilient working face thereon, a plurality of orifices extending through the resilient face, means for supplying gaseous fluid under pressure through said perforations, means for feeding fibrous material to the anvil and across the face at a predetermined rate of speed, and scutching rotors cooperating with the resilient face of the anvil for scutching the fibrous material.

40 3. An apparatus for treating fibrous material comprising in combination an anvil provided with a resilient working face thereon, a plurality of orifices extending through the resilient face, means for supplying fluid under pressure through said perforations, means for feeding fibrous material to the anvil and across the face at a predetermined rate of speed, and scutching rotors arranged in a group for cooperating to scutch the fibrous material and said scutching rotors provided with sets of perforations extending radially outward from the hub of the rotors, and means for supplying fluid under pressure to the rotors for passage through the perforations.

45 4. An apparatus for treating fibrous material comprising in combination an anvil provided with a resilient working face thereon, a plurality of orifices extending through the resilient face, means for supplying air under pressure through said perforations, means for feeding fibrous material to the anvil and across the face at a predetermined rate of speed, and scutching rotors arranged in groups to provide a sinuous path therethrough, said rotors having scutching blades thereon interengaging each other, and said scutching rotors having sets of perforations extending through the hub portion thereof and terminating at the leading edge of the scutching blades, and means for supplying air under pressure for forcing said air through the perforations.

5. An apparatus for treating fibrous material comprising in combination an anvil provided with a resilient working face thereon, a plurality of orifices extending through the resilient face, 5 means for supplying air under pressure through said perforations, means for feeding fibrous material to the anvil and across the face at a predetermined rate of speed, and scutching rotors arranged in a group to provide a sinuous path 10 therethrough, such scutching rotors provided with perforations through which air under pressure is fed to cooperate with the air emitted through the perforations in the resilient face of the anvil and with the air emitted by the respective 15 rotors for expanding or exploding the fibrous material being fed therethrough to facilitate the removal of shives therefrom.
6. An apparatus for treating fibrous material comprising in combination an anvil provided with 20 a resilient working face thereon, a plurality of orifices extending through the resilient face, means for supplying air under pressure through said perforations, means for feeding fibrous material to the anvil and across the face at a predetermined rate of speed, and scutching rotors arranged in a group to provide a sinuous path 25 therethrough, such scutching rotors provided with perforations through which air under pressure is fed to cooperate with the air emitted through the perforations in the resilient face of the anvil and with the air emitted by the respective 30 rotors for expanding or exploding the fibrous material being fed therethrough to facilitate the removal of shives therefrom while such fibrous material is held relatively taut by the engaging blades of a group of scutching rotors.
7. An apparatus for treating fibrous material comprising in combination an anvil, scutching rotors associated therewith and having a greater 35
- surface speed than the speed of feed of fibrous material to the anvil, and means for emitting air through the hub and scutching blades of the rotors for preventing winding up of the fibrous material on the rotors.
8. An apparatus for treating fibrous material comprising in combination an anvil, means for feeding fibrous material therat at a definite rate of speed, a group of scutching rotors associated with the anvil for removing shives from the fibrous material, means for receiving the removed shives including a pair of rotatable members provided with radially extending blades interengaging with each other and rotating at a surface speed greater than the speed of travel of the fibrous material whereby shives from the fibrous material are combed from the fibrous material. 10 15
9. The structure defined as under claim 8, combined with means for supplying air under pressure in the zone between said anvil and said scutching rotors.
10. An apparatus for treating fibrous material comprising in combination an anvil, means for feeding fibrous material therat at a definite rate of speed, scutching rotor means associated with the anvil for removing shives from the fibrous material, means for receiving the removed shives including a pair of rotatable members provided with radially extending blades interengaging with each other and rotating at a surface speed greater than the speed of travel of the fibrous material whereby shives from the fibrous material are combed from the fibrous material, and means for supplying air under pressure through said anvil and directing such air against such fibrous material in the zone of such scutching rotor means. 30 35

ANTON BURKARDT.
